FIG.1

FIG.2

Inventor:
K. Müller

Marker Clark
Attest

UNITED STATES PATENT OFFICE.

KARL MÜLLER, OF KREIENSEN, GERMANY.

WRENCH.

Application filed March 22, 1923. Serial No. 626,982.

To all whom it may concern:

Be it known that I, KARL MÜLLER, a citizen of Germany, residing in Kreiensen, Germany, Harz, Am Brunstein 190, have 5 invented new and useful Improvements in and Relating to Wrenches, of which the following is a specification.

My invention relates to improvements in screw wrenches, and more particularly in 10 wrenches of the type in which one of the jaws is acted upon by a spring tending to force the same towards the other jaw and by a clamping member acted upon by the handle for forcing the same in clamping 15 engagement with said other jaw. The object of the improvements is to provide a wrench of this type which can readily be handled and which is reliable in operation. With this object in view my invention consists in constructing the wrench in such 20 manner that the spring-pressed jaw is automatically locked in clamping position by the operation of the wrench, and remains locked when the handle is accidentally moved in 25 a direction for opening the wrench.

In order that my invention be more clearly understood an example embodying the same has been shown in the accompanying drawing, in which the same reference 30 characters have been used in all the views to indicate corresponding parts. In said drawing,

Fig. 1, is a section of the wrench taken on the line 1—1 of Fig. 2, and

Fig. 2, is a section thereof taken on the line 2—2 of Fig. 1.

In the example shown in the drawing my improved wrench consists of a handle *d* having a jaw *a* mounted thereon by means 40 of a pivot pin *c*, which jaw will hereafter be described as a relatively stationary jaw. The jaw *a* is formed with a guideway *g* which in the example shown in the figures is in the form of a cross. I do not limit 45 myself, however, to this form. In the said guideway a relatively movable jaw *e* is mounted which is formed with an arm *f* fitting in the guideway and passing through a corresponding hole of the stationary jaw. 50 The jaw *e* is formed with a socket or housing *h* enclosing a coiled spring *i*, which spring bears with one end on the bottom of the socket and with its opposite end on a cross-piece *j* secured to the stationary jaw 55 *a*. To the said cross-piece a pin *k* is secured which provides a guide for the spring

i. The arm *f* is formed with a plane bottom face inclined relatively to the guideway and engaged by the top face of a block *m* freely movable within a chamber *b* of the stationary jaw *a* and cut out at its bottom along a circle exactly corresponding to a circular cam *l* formed at the top end of the handle *d* and disposed eccentrically of the pin *c*.

Preferably the engaging faces of the block *m* and the arm *f* are roughened to insure reliable contact between the parts and to lock the movable jaw against in movement out of clamping position. Fig. 1 shows the wrench with a blank *n* clamped between 70 the jaws thereof.

The operation of the wrench is as follows: In the out of use position of the parts, the spring *i* forces the movable jaw *e* towards the stationary jaw. If it is desired 75 to grip a blank *n* the diameter of which is larger than the relative distance of the jaws, the handle *d* is rocked in a counter-clockwise direction in Fig. 1, in order to unlock the block *m* and to release the arm *f* of the 80 movable jaw *e*. Now the movable jaw is retracted by hand away from the stationary jaw and against the pressure of the spring *i*, whereupon the wrench is applied to the blank *n*. Now the movable jaw *e* is released 85 and pressed by the spring *i* against the blank. Thereafter the handle *d* is rocked in a clockwise direction in Fig. 1 for forcing the block *m* by means of the eccentric cam *l* into locking engagement with the arm 90 *f* of the movable jaw *e*. Now the jaw *e* bears on the blank with a pressure a multiple of the force exerted on the handle *d*, so that it can not be moved any more.

In screw wrenches of this type such as are now in use the movable jaw is not always securely locked in the position in which it clamps the blank, and the jaw is sometimes loosened and shifted by accident. By providing a wedge shaped locking member such 95 as the block *m* acting on the inclined bottom face of the arm *f* unlocking of the jaw by accident is impossible, and locking of the closed jaws does not require any considerable force, because by reason of the beveled form of the block *m* the pressure on the arm 100 *f* is sufficient to prevent sliding of the parts *m* and *f* relatively to each other, even if the contacting surfaces are comparatively smooth. For opening the wrench, the handle *d* is turned in a counter-clockwise 105 direction in Fig. 1 and the block *m* is simul- 110

taneously shifted a little to the left, for loosening the parts *m* and *f*, whereupon the jaw *e*, which is now acted upon only by the spring *i*, may be shifted to the left and 5 away from the blank. Now the wrench can be removed from the blank.

I claim:

1. In a wrench, the combination, with a handle having a cam face at one end, of a 10 pivotally mounted jaw, a jaw shiftable relatively to said pivotally mounted jaw, and a block intermediate said shiftable jaw and cam face adapted to be forced by said cam face against said shiftable jaw, the engaging 15 surfaces of the shiftable jaw and the block being inclined relatively to the direction of the movement of the shiftable jaw, said handle forming the only handle of the wrench.

2. A wrench including a relatively stationary jaw provided with a guideway, a relatively shiftable jaw having an arm movably mounted in said guideway, a spring for moving the shiftable jaw in one direction, a locking block for said arm, said arm 25 and locking block being provided with contacting surfaces arranged at an incline to the direction of movement of the shiftable movement of the shiftable arm, and a handle pivotally connected to the relatively stationary jaw and provided with a cam engaging said block for moving the latter.

In testimony thereof I hereinto affix my signature in the presence of two witnesses.

KARL MÜLLER.
